UNITED STATES PATENT OFFICE.

EMIL ISAKSON, OF ANACONDA, MONTANA.

GAME.

1,303,204.

Specification of Letters Patent.

Patented May 6, 1919.

Application filed November 21, 1918. Serial No. 263,606.

To all whom it may concern:

Be it known that I, EMIL ISAKSON, a citizen of the United States, residing at Anaconda, in the county of Deerlodge and State 5 of Montana, have invented new and useful Improvements in Games, of which the following is a specification.

This invention relates to amusement devices, particularly to games, and has for its 10 object the provision of a game board the construction of which is based upon the elements constituting the flag of the United States, and which has inscribed thereon a course divided into forty-eight steps corresponding to the number of stars in the flag, 15 this course having inscribed thereon at intervals the representation of a flag, the steps so marked constituting safety zones, the board being provided inwardly of the 20 course with a plurality of pockets bearing numbers corresponding to the number of stripes in the flag and being provided centrally of all the pockets with a plunger provided with actuating means whereby it may 25 be moved to expel a ball from a socket so that the ball may fall into one of the pockets in order to ascertain how many steps should be taken by a player.

An important object is the provision of a 30 game of this character which will be comparatively simple and inexpensive in manufacture, amusing and instructive in use, and a general improvement of the art.

With the above and other objects and advantages in view, the invention consists in the details of construction to be hereinafter more fully described and claimed, and illustrated in the accompanying drawing in which:—

Figure 1 is a top plan view of the device. 40 Fig. 2 is a bottom plan view.
Fig. 3 is a cross sectional view and
Fig. 4 is a detail sectional view.

Referring more particularly to the drawings the numeral 5 designates the board 45 which is preferably rectangular in shape and which may be formed of any suitable material such as wood, cardboard, or metal. Rising from the center of the board 5 is a cylindrical projection 6 having a frusto-cylindrical upper surface and provided centrally with a cylindrical hole 7. Slidable within the hole 7 is a plunger 8 provided at its lower end with an enlarged head 9 and having disposed thereabout a coiled 55 spring 10 bearing against the underside of

the board 5 and against the upper face of the head 9. Disposed upon the underside of the board 5 and radiating from the plunger 8, is a plurality of arms 11 which are pivotally connected with the board 5 by 60 means of staples 12 secured upon the underside of the board and engaging within notches 13 at the undersides of the arms. At their outer ends, the arms 11 have secured thereto upstanding pins 14 which extend upwardly through the board 5 and which are provided upon their extremities with heads 15. The inner ends of all the arms 11 are beveled as shown at 16 so as to have interfitting engagement with each other 65 beneath the head 9. The tension of the spring 10 urges the head 9 downwardly which holds the inner ends of the arms 11 depressed so that the pins 14 will be in their highest positions. In playing the 70 game, use is made of a ball 17 which is disposable within the hole 7 in engagement with the upper end of the plunger 8.

Disposed in concentric relation to the projection 6 is a flange 18 rising upwardly from the upper surface of the board 5 and disposed between the projection 6 and the flange 18 are radially extending strips 19, fourteen in number. The provision of the strips 19 divides the space between the projection 6 and flange 18 into fourteen pockets 20 the alternate ones of which are preferably differently colored for the sake of ornamentation. One pocket 21 bears the representation of a flag for a purpose to be hereinafter 85 described. The frusto-conical upper surface of the projection 6 has inscribed thereon a series of numbers running from 1 to 13 disposed opposite the pockets 20 as shown, the space opposite the pocket 21 being un-numbered, though understood to be 90 "14." The provision of the thirteen ordinary pockets harmonizes with the provision of thirteen stripes in the flag. The upper surface of the board 5 between the flange 95 18 and the projection 6 is formed preferably frusto-conical so that when the game is played the ball 17 may position itself adjacent the flange 18.

Inscribed upon the surface of the board 105 5 in encircling relation to the flange 18, is a course 22 divided into different steps or spaces 23. The course 22 is preferably of a blue color in accordance with the blue field 110 of the flag and the different spaces are

marked off by preferably red lines, harmonizing with the red stripes of the flag. Furthermore, each space 23 bears a white star as further carrying out the idea of a flag. 5 Every twelfth space bears red, white, and blue stripes to distinguish it from the remaining spaces, these special spaces being designated by the numeral 24 and representing safety zones. Adjacent each of the 10 spaces 24 the surface of the board is inscribed with the word "Safety".

At one side of the board, preferably at a point 90° from the pocket 21, the course 22 is provided with a relatively large space 25 15 adjacent which the word "Home" is inscribed upon the surface of the board. This relatively large space 25 is also provided with red, white and blue stripes but is not provided with the representation of a star. 20 At one side of the board preferably opposite the space 25, the course is provided with another relatively large space 26, provided with red, white and blue stripes, and bearing the representation of thirteen white 25 stars arranged in a circle, this space representing the flag in the early days.

In playing the game, each player is provided with a checker or any other preferred form of "man" which may be the representation of a soldier if desired. The player having the first turn places the ball 17 within the hole 7 and then depresses any one of the heads 15, whereupon the associated arm 11 will be swung upon its pivoting staple 12 so that its inner end will be moved upwardly, moving the plunger 8 upwardly within the hole 7 against the resistance of the spring 10. The ball 17 will then be moved upwardly above the top of the cylindrical projection 6 and will roll off the end of the plunger 8 onto the frusto-conical surface of the projection from which it will drop into one of the pockets 20 or 21. The player is then entitled to move his checker 40 or other counter along the course 22 starting at one side of the large space 25, the number of steps or spaces corresponding to the number of the pockets in which the ball falls. If a player on his first turn, gets 45 12, or if the ball 17 falls in the pocket 21 he will place his counter upon the first space 24 indicating safety. If on his first turn the ball falls into the pocket numbered 13 he cannot play as he cannot pass the safety 50 zone. Each player takes his turn in exactly the same manner until the entire course has been traversed and the one whose counter first reaches the space 25 indicating "home" wins the game. If any player's counter is 55 on any of the ordinary spaces 22 and another player gets a number which would place his counter on the same space the counter previously occupying the space is sent back and must start over. If however 60 65 any counter is on one of these special spaces

24 indicating "safety" it cannot be sent back to start over as any number of counters may occupy these safety spaces. At all times it is not permitted that any player pass over the safety space 24 unless he gets the exact 70 number which added to his previous numbers will entitle him to occupy a safety space, or unless the ball rolls into the pocket 21 designating the flag.

From the foregoing description and a 75 study of the drawings it will be apparent that I have thus provided a very inexpensive and simple game board upon which any desired number of players may play and which is so constructed as to harmonize with 80 the elements of the flag of the United States. It will of course be apparent that the game will be very entertaining and amusing to those using it.

While I have shown and described the 85 preferred embodiment of the invention it will of course be readily understood that I reserve the right to make various minor changes in details of construction such as will not depart from the spirit of the invention nor the scope of the subjoined claims.

Having thus described my invention I claim:—

1. A game board having a playing surface having inscribed thereon a course divided into a plurality of spaces, a cylindrical projection rising from the center of the playing surface and having its upper surface frusto-conical, said cylindrical projection 95 being provided with a hole, a plunger slidably disposed within said hole, means for moving said plunger upwardly to expel a ball placed within said hole, a flange rising from said playing surface concentrically of 100 said cylindrical projection, and a plurality of radially disposed strips extending between said projection and said flange, and defining a plurality of pockets, the upper 105 surface of said cylindrical projection being 110 provided with numerals adjacent said pockets.

2. A game board having a playing surface inscribed with a course divided into a plurality of spaces representing the number 115 of stars in the flag of the United States, certain of said spaces being inscribed with stripes of different colors representing the colors in the American flag, said last mentioned spaces indicating safety zones, a cylindrical projection rising centrally from said playing surface and provided with a hole, a ball disposable within said hole, a plunger within said hole, means for moving said plunger to expel said ball, a cylindrical 120 flange rising from said playing surface concentrically of said projection, and a plurality of radially extending strips disposed between said projection and said flange and defining a plurality of pockets correspond- 125 130

ing to the number of stripes in the flag and an auxiliary pocket bearing the representation of a flag, said cylindrical projection being inscribed with numerals arranged in 5 sequence and corresponding to said first named pockets.

3. A game board having a playing surface having a course inscribed thereon, a cylindrical projection rising from the center 10 of said playing surface and provided with a cylindrical hole, the upper surface of said cylindrical projection being frusto-conical, a plunger slidably mounted within said hole, an enlarged head on the lower end of said 15 plunger, a spring encircling said plunger and abutting against the lower surface of the board and against said head, a plurality

of arms pivoted upon the underside of the board in radial relation to said plunger, up-standing pins on the outer ends of said arms 20 extending through the board and provided at their outer extremities with finger engaging heads, the inner ends of said arms being beveled to engage one another in inter-fitting relation below said head, a ball dis- 25 posable within said hole and expellable therefrom by movement of said plunger, the playing surface of said board being pro- 30 vided with a plurality of pockets surround-ing said central projection into which said ball may fall.

In testimony whereof I affix my signature.

EMIL ISAKSON.
